DESIGN FOR A PORTABLE STITCHER

Roy G. Hoffert, Racine, Wis., assignor to Hoffert
Machine Company, Inc., a corporation of Wisconsin

Application March 4, 1940, Serial No. 20,672

Term of patent 7 years

To all whom it may concern:

Be it known that I, Roy G. Hoffert, a citizen of the United States, residing at Racine, in the county of Racine and State of Wisconsin, have invented a new, original, and ornamental Design for Portable Stitcher, of which the following is a specification, reference being had to the accompanying drawing, forming part thereof.

Fig. 1 is a side elevational view of a portable stitcher showing my new design; and

Fig. 2 is a top plan view thereof, to a reduced scale.

I claim:

The ornamental design for a portable stitcher, as shown.

ROY G. HOFFERT.
